Primary Examiner — Ricky Pham(74) *Attorney, Agent, or Firm* — Ladas & Parry LLP(57) **CLAIM**

The ornamental design for a wine bottle drawer, as shown and described.

DESCRIPTIONFIG. 1 is a perspective view from the front, top, and right side of the wine bottle drawer embodying my new design;
FIG. 2 is a right side elevational view thereof, the left side elevational view being a mirror image thereof;

FIG. 3 is a front elevational view thereof;

FIG. 4 is a rear elevational view thereof;

FIG. 5 is a top plan view thereof;

FIG. 6 is a perspective view from the front, top, and right side of another embodiment of the wine bottle drawer embodying my new design;

FIG. 7 is a right side elevational view thereof, the left side elevational view being a mirror image thereof;

FIG. 8 is a front elevational view thereof;

FIG. 9 is a rear elevational view thereof; and,

FIG. 10 is a top plan view thereof.

The broken lines in the drawings are by way of illustration only and form no part of the claimed design.
